PRODUCTION OF GLYCERINE

Kenneth B. Cofer, Pasadena, Tex., assignor to Shell Development Company, New York, N. Y., a corporation of Delaware

Application April 19, 1954, Serial No. 424,160

6 Claims. (Cl. 260—635)

This invention relates to the conversion of glycerine epihalohydrins, that is, the 1-halo-2,3-epoxypropanes, to glycerine. It deals with an improved process for carrying out this hydrolysis whereby the formation of undesirable by-products is suppressed and high yields of glycerine are obtained in an economical and efficient manner.

A number of different methods have been proposed for synthesizing glycerine. The more successful of these methods depend upon the hydrolysis of mono- and dichlorohydrins. Aqueous metal hydroxide solutions, preferably buffered with a salt of a strong base and a weak acid such as sodium carbonate, are used as the hydrolyzing agent. All of the prior methods have disadvantages of one kind or another in commercial scale operation. By-product formation, especially the formation of higher molecular products such as polyglycerols, is a serious disadvantage. Not only is the yield of glycerine reduced thereby, but also recovery of the glycerine in a pure form may be rendered more difficult as a result. Excessive consumption of reagents and relatively slow reaction making necessary the use of large and expensive reactors are other drawbacks which frequently accompany the methods previously suggested. A further disadvantage of such methods is the need for operating with aqueous solutions of low concentration which makes it necessary to evaporate large amounts of water in order to recover the glycerine in usable form, thus increasing its cost.

It is an object of the present invention to avoid the foregoing disadvantages of prior methods of producing glycerine. Another object is the provision of an efficient method for producing glycerine from 1-halo-2,3-epoxypropanes. Still another object is the hydrolysis of 1-chloro-2,3-epoxypropane under conditions at which glycerine is produced in high yields and in relatively high concentrations which simplify its recovery. Further objects and advantages of the process of the invention will be apparent from the following description of some of the methods which are suitable for carrying it out.

In accordance with the invention, the foregoing and other objects are achieved by carrying out the hydrolysis of 1-halo-2,3-epoxypropanes by short contact at high temperature and pressure with aqueous inorganic carbonate salt solution. The reaction is carried out at a temperature of 130° C. to 200° C. and under pressure of carbon dioxide in the range of 100 to 500 p. s. i. g. for a time of about 5 to 20 minutes. Optimum temperature and residence time vary somewhat with the glycerine concentration of the final, completely hydrolyzed product, as can be seen from the following figures:

Glycerine concentration (percent w.)—	5	10-15	20-25
Temperature, °C.	154-166	157-180	163-180
Residence time, minutes	9-15	7-9	8-10

2

Temperatures and residence times above these optimum ranges promote excessive polymer formation. Those below the optimum ranges lead to incomplete hydrolysis. Temperature and residence time are dependent variables.

5 The optimum ranges given define the limits within which an adjustment of one variable with respect to the other will give the best yield. Usually residence time is controlled by the volume of the reactor and the product throughput required. Optimum yield is then obtained by adjustment of the reaction temperature.

By this method of operation virtually complete conversion of the 1-halo-2,3-epoxypropane can be achieved with very little by-product formation. The reaction can be carried out advantageously with haloepoxy-propane 15 solutions of relatively high concentration. Advantageously, aqueous solutions containing about 15% to 30% by weight of 1-chloro-2,3-epoxypropane are used. In contrast with prior methods of operation, formation of high boiling materials at these high concentrations is very 20 small in the new method. At these concentrations correspondingly concentrated solutions of glycerine are obtained, thus materially reducing the amount of water which must be evaporated in recovering the product.

In addition to improved glycerine yields, an important 25 advantage of the new method over prior practice is the material improvement in alkali economy which it gives. Preferably the process is carried out with an amount of inorganic carbonate such that 2% to about 20%, most preferably about 15% to about 20%, in excess of the 30 stoichiometric requirements remains after completion of the reaction. Smaller amounts of carbonate can be used but less complete hydrolysis usually results, especially when less than 10% excess is employed. Larger amounts of inorganic carbonate do not improve the yield of glycerine and increase the load on the salt removal facilities. The efficiency of inorganic carbonate utilization is further increased by operating with higher concentrations 35 of 1-halo-2,3-epoxypropane. Thus, it has been found that, while maintaining the optimum 15% to 20% excess 40 of sodium carbonate in the product, the consumption of sodium carbonate fell from 79 pounds to 71 pounds per hundred pounds of glycerine produced when the glycerine concentration was increased from 15% to 25% by weight in the effluent, other conditions being the same and with 45 in the previously indicated ranges. This unexpected improvement is believed to be possibly attributable to reduced solubility of non-glycerine precursors in the reaction media at higher concentrations with resulting reduced reactivity of these impurities with carbonate.

50 Carbonates such as sodium carbonate have been suggested as the equivalents of other basic agents such as sodium hydroxide, etc. in the hydrolysis of hydroxy halides. They are not equivalents of such other bases in the hydrolysis of 1-halo-2,3-epoxypropanes, however, and 55 such other bases cannot be substituted for the carbonates used in the present process without sacrifice of important advantages of the invention. To achieve the desired results, inorganic carbonate or bicarbonate salts or mixtures thereof, all of which are included in the term inorganic 60 carbonate as used herein generically, must be employed as the essential hydrolyzing agent. The carbonate ion is an important factor responsible for reduced by-product formation as well as for the rapid catalysis of the hydrolysis and hydration reactions. The carbon dioxide from the reaction may also act as a catalyst as well as a buffer to prevent high pH, which promotes excessive polymer formation. This does not, of course, preclude the use of such minor amounts of other basic agents as

do not essentially alter the reaction or change it substantially from that produced when inorganic carbonates are used as the sole hydrolyzing agent. Thus, for example, more than about 10%–15% by weight of sodium hydroxide in the total alkali fed leads to undesirably increased polymer formation. The carbonate may be advantageously produced by absorbing carbon dioxide liberated in the reaction in caustic soda solution, for which purpose a small excess of sodium hydroxide is desirable.

The preferred inorganic carbonate salts for use in the process of the invention are the alkali metal carbonates and bicarbonates. Sodium carbonate and bicarbonate are especially useful because of their low cost and good solubility in the reaction medium. Alkaline earth metal carbonates can be used but are less desirable because of their low solubility.

The process has been found to be especially useful in the hydrolysis of 1-chloro-2,3-epoxypropane to glycerine. It has been used effectively, however, for the hydrolysis of 1-bromo-2,3-epoxypropane and other 1-halo-2,3-epoxypropanes can be similarly used. The starting 1-halo-2,3-epoxypropane can be formed in the reaction mixture from the corresponding dihalo hydroxypropanes. It is only necessary in such cases to increase the amount of sodium carbonate used by one-half mole for each additional equivalent of halogen present. Mixtures of dichlorohydrins and epichlorohydrin, for instance, those described in Tymstra patent—U. S. 2,605,293, are suitable feed stocks for the new process.

Various procedures can be used in carrying out the process. It can be conducted batchwise, intermittently, or continuously. For the preferred continuous method of operation one can use a reactor which may, if desired, be filled with Raschig rings or other suitable inert packing or may be an unpacked vessel. The reactor can be a horizontal vessel or of the vertical type, in which case the haloepoxypropane or its precursors and the aqueous sodium carbonate solution to be reacted therewith can be fed through the reactor in either upflow or downflow. An unpacked reactor constructed of passes or coils of piping offers advantages, particularly in providing good temperature control in the reaction. In such a tubular reactor a gradual temperature rise as the reaction progresses can be advantageously maintained. More effective utilization of the inorganic carbonate is obtained with such reactors, apparently due to minimized backmixing and resulting suppression of side reactions between the sodium carbonate and impurities in the feed. Formation of undesirable high boiling by-products is also inhibited in tubular type reactors through minimized backmixing of glycerine with incompletely hydrolyzed reaction mixture. One can also use a combination of a tubular reactor with a tank reactor in which the initial stages of the reaction, corresponding to that taking place in, say, about the first one-fifth to about one-third of the total reactor volume in which a major portion of the hydrolysis occurs, are carried out in heated reaction tubes. The attached drawing is a schematic diagram of one suitable reaction system of this type in which the units are not drawn to scale.

In the drawing, 1 represents a storage tank for 1-halo-2,3-epoxypropane or precursor, or mixtures thereof, which is to be hydrolyzed to glycerine in accordance with the invention. This feed material is withdrawn by line 2 and fed, together with aqueous sodium carbonate solution introduced by line 3, to pump 4 from which it is passed to preheater 5. In this preheater, as shown, the feed mixture is heated by indirect heat transfer from steam introduced by line 6, the condensate from which is withdrawn by line 7. Other heating media can, of course, be employed. The thus heated reaction mixture withdrawn by line 8 can be further heated by direct injection of high pressure steam introduced by line 9. Heating by direct injection of steam can be used alone to bring the reaction mixture to the desired temperature within the

range of 130° C. to 200° C. as previously indicated. The thus preheated mixture, under a pressure of 100 to 500 p. s. i. g. sufficient to maintain a liquid phase system, is fed to reactor 10 containing a sufficient number of passes of pipe 11 to provide about one-fourth of the total required reactor volume. Effluent from reactor 10, still at reaction temperature and pressure, passes by line 12 to tank-type reactor 13 in which the hydrolysis is completed. A total residence time of about 5 to 15 minutes in reactors 10 and 13, which are advantageously insulated to conserve heat and can be provided with additional heating means if desired, is suitable. The reacted mixture is taken off by line 14, containing pressure reducing valve 15, to flash drum 16 in which carbon dioxide is separated and removed by line 17 from aqueous glycerine solution taken off by line 18. The excess sodium carbonate in the glycerine solution is neutralized with acid introduced by line 19 in neutralizer 20 from which the solution is taken off by line 21 and fed to evaporation and distillation units 22 and 23. The salt produced is removed conventionally and taken off by line 24, while the water and low boiling impurities are taken off by line 25 and the high boiling impurities by line 26. The product glycerine is recovered by line 27.

The carbon dioxide taken off by line 17 from the flash drum 16, together with carbon dioxide removed by line 28 from neutralizer 20, is fed to absorber 29. In the absorber the gaseous carbon dioxide is passed countercurrent to sodium hydroxide solution introduced by line 30. The resulting sodium carbonate solution is withdrawn by line 31 and returned to the reaction by line 3 together with make-up sodium carbonate solution supplied by line 32 in an amount sufficient to provide one equivalent of base per equivalent of reactive halogen in the feed stream from tank 1, and preferably about 5% to 20% in excess of such stoichiometric requirement.

By this method of operation, the amount of base required, i. e. sodium hydroxide supplied by line 30 and sodium carbonate fed by line 32, is 20% to 35% less than when the hydrolysis is carried out with buffered sodium hydroxide, according to the best prior practice. The amount of acid which must be fed by line 19 and the amount of salt which must be removed from the glycerine are proportionately reduced. Also, the yield of glycerine is significantly higher, especially due to the reduced formation of undesirable high boiling products which are only $\frac{1}{10}$ to $\frac{1}{4}$ of the amount previously produced.

The following examples illustrate these and other advantages of the new process as applied to the hydrolysis of 1-chloro-2,3-epoxypropane.

EXAMPLE I

1-chloro-2,3-epoxypropane (produced by steam stripping an allyl chloride chlorohydrination product in the presence of a base), analyzing about 75% by weight 1-chloro-2,3-epoxypropane, was used as feed to a pipe reactor constructed of 100 feet of 6-inch steel pipe arranged in a vertical stack of four horizontal passes in series. The 1-chloro-2,3-epoxypropane and aqueous sodium carbonate feed streams were mixed in a manifold on the suction side of a reactor feed pump and charged to the reactor at 150 p. s. i. g. Heat for the reaction was supplied by direct injection of 175 p. s. i. g. steam at a point about four feet downstream from the feed inlet. Product from the reactor was reduced to atmospheric pressure and the aqueous glycerine separated from the carbon dioxide. The carbon dioxide was absorbed in sodium hydroxide solution to produce sodium carbonate for further hydrolysis, and the aqueous glycerine solution was neutralized, evaporated and distilled to obtain pure, refined glycerine. The following are typical results obtained in runs at different concentrations of 1-chloro-2,3-epoxypropane expressed as concentration of equivalent glycerine in the reacted mixture, using the

reaction conditions in the ranges found to be optimum for these concentrations:

	Equivalent Glycerine Concentrations		
	5%	15%	25%
Temperature, ° C.....	154-166	157-180	163-180
Residence Time, minutes.....	8-15	7-9	8-10
Excess Na ₂ CO ₃ in Product, percent w.....	15-20	15-20	15-20
Glycerine Conc. in Product, percent w.....	4-6	13-18	20-25
Alkali Consumption, lbs. Na ₂ CO ₃ Fed/100 lbs. Glycerine Produced.....	81-84	76-79	64-72
NaCl/Glycerine Ratio in Product.....	1.10	0.71	0.67
H ₂ O/Glycerine Ratio in Product.....	18.0	5.0	2.5
Yield (Percent Glycerine Precursors Fed):			
Glycerine.....	98.5	98.5	97.1
Polymer.....	1.3	1.0	2.6
Unhydrolyzed.....	0.2	0.5	0.3

The temperatures referred to herein and in the appended claims are the maximum temperatures attained during the reaction. Some reaction takes place at the lower temperatures at which the reactants are mixed and pumped to the reactor before the final heating to the specified reaction temperature is carried out.

The residence times reported in the foregoing table are calculated by dividing the reactor volume in gallons by the feed rate in gallons per minute. The actual liquid residence time in the reactor is somewhat lower due to the reactor volume occupied by the carbon dioxide liberated during the reaction.

EXAMPLE II

Tests of batch hydrolysis were made in a high pressure, stainless steel reactor provided with a high speed mixer and an internal heating coil. The reactor was charged with aqueous sodium carbonate solution which was heated, then the 1-chloro-2,3-epoxypropane (78.9% potential glycerine) was added and the reactor closed. The mixture at 80° C.-90° C. was then heated to the reaction temperature. When the evolved carbon dioxide has raised the pressure in the reactor to the desired level, the pressure was maintained constant for the remainder of the reaction period by releasing gas through a bleed-off valve to a scrubber in which the carbon dioxide was absorbed in 20% sodium hydroxide solution. The glycerine yield was determined from analyses of the feed stream, reactor product, reactor wash water, and the vent scrubber solution, after which hydrolyzer product was worked up in the usual way for recovery of pure glycerine.

The following are the results of typical runs under different reaction conditions.

Feed Composition (Percent w.)			Stoichiometric Excess of Na ₂ CO ₃ , Percent	Maximum Reaction Temp. (° C.)	Maximum Reaction Pressure (p. s. i. g.)	Reaction Time ¹ (min.)	Unhydrolyzed Glyc. Precursors (Percent w.)	High Boiling Product (Percent w.)	Glyc. Yield (Percent w.)

24.6	15.5	59.9	10	152	410	16	None	-----	99.2

¹ Reaction time is the total residence time in the reactor including the heat-up time.

EXAMPLE III

The effect of variations in the maximum operating temperature upon the results of hydrolysis of mixtures of 1-chloro-2,3-epoxypropane (75%-80%) with about 20%-25% of glycerine dichlorohydrins was determined in two series of tests under different conditions. One series of tests was made in the tubular reactor used in Example I and the other tests were carried out in a tubular reactor

two feet in diameter and 16½ feet in height. In this reactor the 1-chloro-2,3-epoxypropane feed (78%-84% glycerine precursors, the balance organic impurities including trichloropropane, etc.) to the unit was mixed with sodium carbonate in a manifold in the suction side of a single stage, double suction centrifugal pump capable of developing 165-175 pounds pressure. The pump served to mix and disperse the reactants as well as to pressure the unit. The pump discharged into the bottom of the reactor which operated near 150 p. s. i. g. Heat to the reactor was supplied by injection of 175-pound steam into the bottom of the unit and by heat of reaction. Product withdrawn from the top of the reactor was routed through back-pressure controller into a phase separator where the aqueous glycerine product was separated from the carbon dioxide. The product layer was removed for analysis and recovery of the glycerine, and the carbon dioxide was absorbed in sodium hydroxide to produce sodium carbonate solution for further hydrolysis.

29.4	0.2	2.8	

I claim as my invention:

1. A process for hydrolyzing a 1-halo-2,3-epoxypropane which comprises contacting the 1-halo-2,3-epoxypropane with an aqueous solution containing at least a stoichiometric amount of an inorganic carbonate of the group consisting of the alkali metal and alkaline earth metal carbonates as the essential hydrolyzing agent at a temperature of 130° C. to 200° C. in the presence of carbon dioxide under a pressure in the range of 100 to 500 p. s. i. g.

5 sufficient to maintain the reactants in the liquid phase for about 5 to 20 minutes, and recovering glycerine from the resulting reaction mixture.

10 2. A process in accordance with claim 1 wherein alkali metal carbonate hydrolyzing agent is used in an amount of about 2% to 20% in excess of the stoichiometric requirement for the hydrolysis.

15 3. A process in accordance with claim 1 wherein the reaction is carried out with an aqueous solution containing about 15% to 30% by weight of 1-chloro-2,3-epoxy-20 propane.

25 4. A process for producing glycerine which comprises hydrolyzing 1-chloro-2,3-epoxypropane by contact with an aqueous solution containing at least a stoichiometric amount of sodium carbonate as the essential hydrolyzing agent at a temperature of 150° C. to 180° C. in the presence of carbon dioxide under a pressure in the range of 100 to 500 p. s. i. g. sufficient to maintain the reactants in the liquid phase for about 5 to 15 minutes.

30 5. A process in accordance with claim 4 wherein the reaction is carried out with about 10% to 20% excess of sodium carbonate above the stoichiometric requirement for hydrolysis of the starting material.

35 6. A process in accordance with claim 4 wherein the reaction is carried out with an aqueous solution containing about 15% to 30% by weight of 1-chloro-2,3-epoxypropane.
